UNITED STATES PATENT OFFICE.

VALENTINE F. DELMUÉ, OF LOS ANGELES, CALIFORNIA.

HAIR CRIMPER.

Application filed February 29, 1924. Serial No. 696,006.

To all whom it may concern:

Be it known that I, VALENTINE F. DELMUÉ, a citizen of the United States, residing at Los Angeles, in the county of Los Angeles and State of California, have invented certain new and useful Improvements in Hair Crimpers, of which the following is a specification.

The present invention relates to a hair crimpler and has for its prime object to provide a device of this nature capable of crimping or saving hair and particularly designed for use with bobbed hair.

Another object of the invention is to provide a hair pin of this character which due to its simple design in two parts may be economically constructed and although embodying a minimum amount of labor and machine work in its manufacture, at the same time is capable of operating in a simple and easy manner providing for the long and useful life of the several parts of which the hair crimpler is composed.

A still further object of the invention is to provide a hair crimpler of this nature which may be readily engaged with or disengaged from the hair.

With the above and numerous other objects in view as will appear as the description progresses, the invention resides in certain novel features of construction, and in the combination and arrangement of parts as will be hereinafter more fully described and claimed.

35 In the drawing:

Figure 1 is a perspective view of the hair crimpler embodying my invention showing the same in an open position.

Figure 2 is an elevation of the hair crimpler showing the same in a closed position.

Figure 3 is a detail perspective of one end of one of the crimp bars, and

45 Figure 4 is a detail perspective of one end of the other crimpler bar.

Referring to the drawing in detail it will be seen that 1 designates a substantially rectangular frame which is provided at one end with a U-shaped extension 2 and at 50 its other end with a pair of apertured ears 3 through which passes a bolt 4. A pair of crimp bars 5 and 6 are associated with the frame and these bars are of similar construction. Each bar is provided with an intermediate longitudinally extending V-

shaped portion 7. These bars 5 and 6 are pivoted on the bolt 4 so as to extend longitudinally of the frame. The convex side of one V-shaped portion 7 is provided with a snap fastening element 8 while the concave side of the other V-shaped portion 7 is provided with a snap fastening element 9.

In order for the crimp bars 5 and 6 to be separable, the space between the apertured ears 3 is slightly greater in width when bolted as at 4, than the width of the U-shaped extension 2.

It is to be understood that the frame 1 and the bars 5 and 6 are preferably formed of some resilient material. The strands of hair are placed between the bars 5 and 6 when they are in an open position such as is shown in Figure 1 and the bars are then alined with each other so that the snap fastening elements 9 and 10 may be engaged. 70 Thus the bars lie alongside of each other and may be pivoted so that their free ends are disposed in the U-shaped extension 2 and frictionally held therein thus preventing accidental separation of the bars 5 and 6. The strands of hair may also be passed around the side rails of the frame 1. It is, also, evident that the device may be used in other ways than that which I have outlined above. Numerous changes in the 80 details of construction and in the combination and arrangement of parts may be resorted to without departing from the spirit or scope of the invention as hereinafter claimed or sacrificing any of its advantages. 90

Having thus described my invention, what I claim as new is:

1. A hair crimpler of the class described including a pair of bars pivotally associated with each other at adjacent ends and provided with longitudinally extending V-shaped mid-portions one adapted to fit within the other, and means at the free ends of the bars for holding them together. 95

2. A crimpler of the class described including a frame, a pair of crimp bars pivotally mounted in the frame, each crimp bar provided with a longitudinally extending V-shaped mid-portion, one V-shaped mid-portion adapted to be receivable within 105 the other, and means associated with the bars for holding them alongside each other.

3. A crimpler for the class described including a frame, a pair of crimp bars pivotally mounted in the frame, each crimp bar 110

provided with a longitudinally extending V-shaped mid-portion, one V-shaped portion adapted to be receivable within the other, means associated with the bars for holding them alongside each other, said frame provided with a U-shaped extension for receiving the free ends of the bars so as to hold said bars frictionally in order that they

may be disposed alongside of each other within the frame.

In testimony whereof I affix my signature in presence of two witnesses.

10

VALENTINE F. DELMUÉ.
